US00D577293S

(12) **United States Design Patent**
Snyder et al.

(10) **Patent No.:** US D577,293 S
(45) **Date of Patent:** ** Sep. 23, 2008

(54) **BOTTLE**

- (75) Inventors: **MarySue Snyder**, Purchase, NY (US);
Ron Pence, Purchase, NY (US);
Kenneth Hirst, New York, NY (US);
Sam Wilson, Tampa, FL (US)
- (73) Assignee: **PepsiCo, Inc.**, Purchase, NY (US)
- (**) Term: **14 Years**
- (21) Appl. No.: **29/304,199**
- (22) Filed: **Feb. 27, 2008**

Related U.S. Application Data

- (62) Division of application No. 29/276,734, filed on Feb. 2, 2007, now Pat. No. Des. 566,578.

(57) **CLAIM**

The ornamental design for a bottle, as shown and described.

DESCRIPTION

FIG. 1 is a front left perspective view of a bottle showing a first embodiment of our new design;

FIG. 2 is a front view thereof;

FIG. 3 is a right side view thereof;

FIG. 4 is a left side view thereof;

FIG. 5 is a rear view thereof;

FIG. 6 is a top view thereof;

FIG. 7 is a bottom view thereof;

FIG. 8 is a front left perspective view of a bottle showing a second embodiment of our new design;

FIG. 9 is a front view thereof;

FIG. 10 is a right side view thereof;

FIG. 11 is a left side view thereof;

FIG. 12 is a rear view thereof;

FIG. 13 is a top view thereof; and,

FIG. 14 is a bottom view thereof.

The dot-dot-dash-dot-dot-dash broken lines shown in the drawings define the boundary lines of the claimed design. The dash-dash-dash-dash broken lines shown in the drawings are for environmental purposes only and form no part of the claimed design.
